APPARATUS FOR MAKING SHAPE RETAINING FIBER MATTRESSES

William H. Waters and Jacob S. Kern, Fleetwood, Pa., assignors to Fleetwood Craftsmen, Inc., Fleetwood, Pa., a corporation of Pennsylvania

Application May 11, 1932, Serial No. 610,636

3 Claims. (Cl. 28—4)

This invention relates to an improved mattress, cushion or the like, of needled fibers of curled hair, or other animal or vegetable fibers, and to a machine and process of fabricating the same into a cohesive shape-retaining fashioned unit capable of being handled without disintegrating, and requiring no casing nor tufting to preserve its predetermined configuration.

Mattresses and the like of such curled fibers have heretofore been made by "stuffing" an amount of the fibers into a prepared casing, closing the latter by seaming, and then "tufting" to more or less secure the encased fibers from shifting into an uneven and lumpy contour. Another known method has been to fill a casing with one or more lays of needled fiber batting cut from a roll of the latter, and then seaming the casing and tufting as before; such batten roll having but a loose cohesion and cutting the same to lengths starting its disintegration.

In both the above heretofore known methods the avoidance of fiber shifting has been only partly successful, and the renovating of the mattress has necessitated a complete remaking operation, as the cleaning and washing of the removed fiber contents destroys any unitary and shape-retaining semblance they may have had when secured in the prepared casing.

Various efforts to make the fiber contents a cohesive unit have heretofore been attempted, including their needling to sheets of woven fabric or combination with other materials, but none have been successful in producing a complete finished fiber article of compact cohesive resiliency capable of being handled during renovating without disturbing its formation and fixedly retaining its given structure independent of any confining casing or tufting requirement.

In addition to the improved shape-retaining cohesive formation of the fiber mattress above set forth, the present improvements provide for a nicely predetermined resilient compactness of the component fibers throughout the whole or in selected areas thereof, and for any desirable variation in shape and thickness.

The present improvements and the machine and method employed in producing the same are more fully described in the following specification in connection with the accompanying drawings forming part thereof, and the novel features particularly set forth in the appended claims.

Fig. 1 indicates in perspective a rectangular mattress of curled fibers made in accordance with the present improvements.

Fig. 2 shows a step in the method of producing the mattress shown in Fig. 1, the curled fibers being loosely laid in a form of the determined size desired for the finished article.

Fig. 3 shows a further step in the method, the loosely laid fibers indicated in Fig. 2, being confined between the slatted bottom and cover of the form under a predetermined compression.

Fig. 4 is a diagrammatic cross sectional showing, taken on the line 4—4 of Fig. 5, indicating a machine having reversely directed needles reciprocatively operative to pass between the slats of the top and bottom of the progressively advanced form shown in Fig. 3, and to pierce the confined fibers through and through to weave the mass into a cohesive unit by entwining engagement of said fibers.

Fig. 5 is a partial side elevation of the structure shown in Fig. 4, the view being taken on the line 5—5 of the latter.

Fig. 6 is a corresponding sectional view taken on the line 6—6 of Fig. 4.

As an essential step in producing a mattress, cushion or the like according to the present invention, a form of the predetermined size is employed in which the curled fibers are loosely laid by hand and piled up to a height sufficient to produce a desired resiliency when a form cover is pressed downward thereon and locked in closed position.

A form of the above nature is indicated in Figs. 2 and 3, and is shown as a rectangular frame, the sides 10, and ends 11 having a height equal to the desired thickness of the finished mattress, and the bottom 12 and cover 13 being formed of slats 14, 14, preferably set edgewise and extending transversely from side to side. The bottom 12 is shown as united to the sides 10 and ends 11 to form an integral rigid frame, and the removable cover 13 is indicated as secured to said frame by hasps 15. And to facilitate the laying of the curled hair in the frame to the desired height, temporary side 10a and ends 11a may be employed, which are removed preliminary to positioning and fastening the cover 13 in place.

With the form above described, which it will be understood may be of any predetermined size, shape, and thickness, the curled fibers are carefully laid and confined by the frame, permitting piling up as desired, particularly in selected areas subjected to greatest wear, and when so laid, the temporary sides 10a and 11a are removed, and the cover 13 put in place to compress the laid fibers to the desired thickness of the form, in

which position the cover is retained by the hasps 15, as indicated in Fig. 3. The confined fibers are thus compressed and held to the shape of the form, and are ready to be cohesively united 5 in such shape by a needling operation adapted to integrally weave them together by intertwining the fibers; such needling being effected between the spacings of the slats 14 without releasing the compression on the confined mass.

10. A machine for needling the fibers thus held compressed in the form, is indicated in Figs. 4, 5 and 6, and essentially comprises a slide way or supporting track formed by spaced side frames 20, 20 carried by uprights 21, 21, and other supports, not indicated, spaced along the lengths of said side frames to maintain them in horizontal alignment. Each side frame 20 is shown as of angular cross-section with a track 22 for the form to rest upon and a channel 23 for a 20 feed chain 24. Each chain 24 is preferably an endless belt having a return bend beneath its side frame and carried on sprockets at each end of the latter, only one sprocket being indicated at 25 in Fig. 4; and a transverse shaft 26 is shown as connecting the two sprockets at one end, and having a ratchet wheel 27 and concentrically pivoted pawl 28 arranged to intermittently rotate said chain, any suitable connection, as link 29, 29 (Fig. 4) coupling the form 30 thereto to be progressively moved forward by said chain step-by-step on tracks 22, 22.

The uprights 21, 21 are shown as arranged on opposite sides of the spaced side frames 20, 20, and act as supports for vertically movable bars 30 and 31, arranged respectively above and below the side frames 20, 20, and each provided with a row of fiber-interlacing needles 32 and 33 respectively directed toward the slide way formed by said frames 20, 20. Bar 30 is shown as projecting through guide way slots 34, 34 in each upright and mounted in slide members 35, 35 vertically movable on said uprights, and bar 31 is shown as similarly projecting through guide way slots 36, 36, and mounted in slide members 37, 37 on said uprights.

45. Reciprocatice movement is imparted to bar 30 by a transverse shaft 40 shown as having end discs 41, 41, each having a pitman connection 42, 42 to said bar, and bar 31 is shown as similarly reciprocated by a separate transverse shaft 45 having end discs 46, 46 with pitman connections 47, 47.

In order to vary the stroke of the reciprocative bars 30 and 31, their pitman connections to their 55 respective discs 41, 41 and 46, 46 may have a slotted adjustment as shown, and to provide for proper location of the bars 30, 31 for varying thicknesses of passing forms, the shafts 40 and 45 are preferably mounted for vertical adjustment, as follows: Shaft 40 is shown as projecting through guide slots 50, 50 in uprights 20, 20 and mounted in slide members 51, 51 on said uprights, screw rods 52, 52 engaging said slide members to vertically adjust their positions on 60 said uprights, and said screw rods each having a bevel gear 53, 53 meshing with bevel gears on a hand turned shaft 54 for jointly and simultaneously rotating said screw rods. Shaft 45 is shown as similarly projecting through slots 55, 55 in said uprights, mounted in slide members 56, 56 adjustably positioned by screw rods 57, 57 having bevel gears 58, 58 jointly operated by a hand turned shaft 59.

70. It is desirable that shafts 40 and 45 be jointly rotated, and to this end slide members 51, 51

carry a second transverse shaft 60 shown connected to shaft 40 by suitable gears 61, 62, and slide members 56, 56 similarly carry a second shaft 65 connected to shaft 45 by gears 66, 67. Shafts 60 and 65 are jointly connected by a vertical shaft 70 having suitable bevel gear connections to said shafts 60 and 65 as shown, and said vertical shaft is shown extended above slide members 51, 51, and its bevel gear 71 driving shaft 60 is keyed on shaft 70 and slidably thereon to provide for vertical adjustment of the slide members 51, 51 and 56, 56 as will be readily understood. Power may be applied, as indicated by a pulley wheel on shaft 65.

75. Racking rotation of feed chain 24 is indicated as effected through a bell crank 75 mounted on a side frame 20 (Fig. 5) with one arm connected by an adjustable link 76 to a slide block 35, and its other arm connected by a rod 77 to the concentrically pivoted pawl 28 operating rack gear 20 25.

From the foregoing description it will be readily seen that the machine operates to jointly reciprocate the needles into and through the fibers confined and held in the form, said needles entering between the slots of the top and bottom of said form, and said form being racked forward between each needling reciprocation to advance the next space. The needle stroke, and vertical adjustment of shafts 40-60 and 45-65 30 above set forth, provide for any variation in thickness of form and insure complete through and through needling for any size, and the adjustable link 76 for varying the step-by-step feed of the form to suit varied slot spacings. The 35 form of needles employed may be of any ordinary construction, but a hooked needle is preferred which passes freely through the fibers in one direction and engages to entwine them in the reverse reciprocation.

40. The needling effected by the machine above set forth operates reversely through each slat opening, and, as shown, extends closely to each side and end of the form so that the fibers confined by the walls of the frame are entwined and interengaged close to the latter insuring a 45 complete cohesive union throughout with finished edges and surfaces.

A mattress made in accordance with the present invention is indicated in Fig. 1, the size 50 thereof being of the predetermined size of the form employed, and the compact resilient thickness determined by the height of the walls of the form used, and the amount of curled fibers employed and compressed in said form, and its cohesive union and retention of the shape of the 55 form is insured by its needling while held compressed in said form. Such needling of the fibers held compressed in the form insures their cohesive weaving into a shape-retaining tenacious mass, and with the needling carried close to the edges of the form, the sides 80 and ends 81 of the mattress are finished and firmly held with no ragged free ends, and the top 82 and corresponding bottom are also finished and fixedly held due to the maintained pressure of the 60 form during production. There is no mechanical picking required in its making and no cutting after being made, both tending to break the long fibers into short ones not securable by 65 needling, and no other material or interengaged burlap is required to insure its unitary cohesion, producing an improved mattress solely of one component fiber constituent, solidly built to specific dimension of width, length and height, pro- 75

viding increased resilience and longevity of use. The forms employed may be of any irregular shape, and the fibers laid in different degrees of thickness to provide wear resisting areas of 5 greater density.

From the foregoing description it is believed the nature of the present improvements and the method and machine for making the same will be readily understood, and the specific structure shown may of course be modified within the 10 scope of novelty defined in the following claims.

What we claim is:

1. In a machine for needling curled fibers, the combination with a pair of horizontal side frames 15 having a form-carrying slide-way, a pair of endless feed belts traversing the latter, opposed uprights intermediate the length of said side frames, and needle-carrying bars above and below said slide-way mounted to reciprocate on said uprights and having fiber-entwining needles directed toward said slide-way; of a drive shaft associated with each needle-carrying bar mounted for vertical adjustment on said uprights and having a reciprocative connection to its respective bar and a drive connection to a vertical drive shaft, and separate means for adjusting each shaft relative to said slide-way; the shaft associated with one of said needle bars having

a sliding drive connection to said vertical drive shaft to permit vertical adjustment of either shaft.

2. An open-top frame having solid side and end walls and a rigid slatted bottom adapted to confine unevenly piled-up curled fibers to its determined size and shape, and a removable slatted top adapted to be seated on said frame by compression of the fibers to a determined uniform thickness of uneven density, and locking means 10 to hold said slatted top in position; the slats of the rigid bottom and removable top being in vertical alinement to permit a reversely directed through-and-through needling operation between the slats.

3. An open top frame having solid side and end walls and a slatted bottom adapted to confine determinedly placed piled-up curled fibers, and a removable slatted top adapted to be seated on said frame by compression of the fibers to the 20 size and shape of said form, and locking means to hold said top in seated position; the slats of the rigid bottom and removable top being in vertical alinement to permit a reversely directed through-and-through needling operation be- 25 tween the slats.

WILLIAM H. WATERS.
JACOB S. KERN.
